ELECTRIC SOUND-REPRODUCING APPARATUS

Adolph A. Thomas, New York, N. Y., assignor to
 Radio Corporation of America, a corporation
 of Delaware

Application March 1, 1929, Serial No. 343,627
 Renewed November 12, 1935

25 Claims. (Cl. 274—10)

This invention is for an electric phonograph capable of playing continuously a plurality of disk records by automatic mechanism of simple construction and reliable operation. My new instrument is particularly useful in talking movies of the phonograph type in which more than one record is required to accompany a long picture with speech or music without interruption. Heretofore, at least two separate phonographs were employed, each with its own motor and reproducer, and automatic synchronizing mechanism of complicated structure was necessary to start the second phonograph just before the record of the first machine reached the end of its travel. Such a piece of apparatus was not only intricate, but very expensive, and wholly unfit for household use.

It is the object of my invention to provide a multiple-disk phonograph in which disk records are automatically played in pairs, each pair having a single reproducer. The basic feature of my machine comprises a pair of records arranged to rotate simultaneously in opposite directions and in contact with each other at the edge. The first record is played from the center toward the edge, and the second is played from the edge toward the center by the same reproducer. The spiral tracks of the two contiguous records are united across their peripheral point of contact, thus forming a double continuous spiral running from the center of the first record to the center of the second. The reproducer travels along a diametric line across the two records, which are supported on their respective turntables in such relation as to unite the spiral tracks at the point of contact. If more than one pair of records are used, I make provision for automatically starting the operation of a succeeding pair of records when the reproducer of the preceding pair is at the end of the spiral groove. These automatic starting connections are quite simple and involve little more than a mere duplication of turntables and driving motors. For a household machine, one pair of turntables is sufficient; and in a machine designed for talking-movie equipment, not more than two pairs of turntables are needed.

The novel features and practical advantages of my improved phonograph will be understood from a description of the accompanying drawings, in which—

Fig. 1 is a diagrammatic plan view of a pair of disk records constructed and arranged in accordance with my invention to provide a continuous playing groove from the center of one record to the center of the other;

Fig. 2 represents a portion of the contiguous records on an exaggerated scale to show more clearly the uniting of the two spiral grooves across the point of contact;

Fig. 3 is a cross-section of Fig. 2 on line 3—3;

Fig. 4 shows the mounting of the reproducer and electromagnetic means for normally holding it out of playing position;

Fig. 5 is a plan view of the machine for one pair of turntables;

Fig. 5a illustrates the details of a motor-controlling switch used in Fig. 5;

Fig. 6 is a front view of Fig. 5, partly in section, to show certain parts beneath the motor board;

Fig. 7 is a plan view of a machine having two pairs of turntables and circuit connections for automatically starting the operation of the second pair of records;

Fig. 8 shows the reproducer in side view at the end of the spiral groove, which is adapted to close one of the controlling circuits indicated in Fig. 7;

Fig. 9 is a rear view of the reproducer;

Fig. 10 is a plan view, partly in section, showing the mounting of the reproducer and the electromagnet which releases the reproducer arm at a predetermined moment; and

Fig. 11 shows an enlarged detail of a motor switch operated by the reproducers in the machine of Fig. 7.

The basic idea of my invention is diagrammatically represented in Fig. 1, where we have a pair of disk records 10 and 12 mounted on turntables to rotate simultaneously in opposite directions at the same speed. The central circles 13 and 14 may be regarded as the turntable shafts on which the records rotate. The record 10 has a spiral sound groove 15 played from the center toward the edge, and the record 12 has a spiral sound groove 16 played from the edge toward the center. It is understood, of course, that these sound grooves are indicated merely in a diagrammatic way. In the actual records these grooves are exceedingly fine and run to several hundred lines per inch. The circle 17 at the center of record 10 is a starting groove for the stylus of the reproducer and leads into the spiral sound groove 15 at the point 18. The record 12 has a circular groove 19 at the center into which the stylus is automatically guided after leaving the spiral track 16. This track may be assumed to end at the point 20, which is diametrically opposite the starting point 18 of track 15. The imaginary line 21 indicates the path of travel of the playing stylus,

as will be more clearly understood after I have described the mounting of the reproducer.

The terminal portion 22 of spiral groove 15 and the initial portion 23 of spiral groove 16 extend toward each other in alignment and unite at the point 24, which lies in the imaginary line or path 21 traveled by the playing stylus. We thus have a substantially continuous sound groove consisting of two opposite spirals 15 and 16 beginning at 18 and ending at 20. To obtain this continuous double sound groove, the records 10 and 12 are mounted in contact at their peripheries. It is advisable to use suitable means for holding the playing surfaces of the records in alignment at the place of contact. A simple way to insure this alignment is to provide one record 15 with a peripheral groove 25, and the other record with a peripheral projection 26 adapted to fit into the groove 25, as best shown in the exaggerated view of Fig. 3. The records are thereby interlocked at the point of engagement and yet are free to rotate in opposite directions, as indicated by the arrows 27 and 28 in Fig. 1. It is necessary to place the records 10 and 12 on the turntables in predetermined relation, so that the spiral grooves 15 and 16 shall unite at the point 24 every time the outer ends of the grooves cross the diametric line 21. The proper positioning of the records may be compelled by the simple expedient of providing the turntables with pins and the records with correspondingly arranged holes to receive the pins. For example, in Fig. 1 the turntable of record 10 has a pin 29 which passes through a hole in the record, and the turntable of record 12 has two pins 30 which pass through correspondingly arranged holes in the record. This arrangement of pins and holes compels the mounting of the two records on their turntables in one position only, so that the spiral grooves 15 and 16 will unite at 24 every time the rotating records reach the position illustrated in Figs. 1 and 2.

If a playing stylus is so mounted as to move laterally in a path indicated by the imaginary diametric line 21, it is evident that the stylus point will travel without interruption from the starting point 18 of the spiral groove 15, across the point 24 into the spiral groove 16, finally reaching the circle 19. By making the peripheral projection 26 with a slanting edge, as shown in Fig. 3, the stylus point will always be guided safely from the terminal portion 22 of spiral 15 across the bridging point 24 into the initial portion 23 of spiral groove 16. Ordinarily, the transition of the playing stylus from one record to the other will not be noticed acoustically, but even if there should be a brief interruption at the moment when the stylus crosses the point 24, it will have no marring or objectionable effect on the reproduction. In all phonograph records there are pauses in the speech or music, and one of these pauses may well occur at the crossing point 24.

Referring to Figs. 5 and 6, the records 10 and 12 are placed on a pair of turntables 31 and 32, which are mounted on and rotate with the upright shafts 13 and 14, previously mentioned. The shaft 13 extends through the motor-board 33 and is supported at its lower end in a suitable bearing 34 carried by a fixed bracket 35. A sleeve or hub 36 on shaft 13 carries a gear 37 arranged in mesh with a similar gear 38 fixed on the other turntable shaft 14. The meshing point of the gears 37 and 38 is indicated at 39, where the gears are shown in section for clearness. The lower end of shaft 14 rests in a bearing 40. An electric motor 41 has a shaft 42 carrying a worm pinion 43 arranged in mesh with a

worm gear 44 on shaft 14, whereby the movements of the motor shaft are transmitted to the turntables 32 and 31 in properly reduced ratio. In present day phonographs, the turntable is usually driven at the rate of about eight revolutions per minute. Instead of using separate gear wheels 37 and 38, it is evident that the turntables 31 and 32 could be provided at the edge with meshing gear teeth. While only one of the shafts 13 and 14 is connected directly to the driving pinion 43, both shafts could be connected to the motor independently of each other, but that is not necessary. In the broader aspect of my invention, any suitable driving connections may be employed to rotate the turntables 31 and 32 simultaneously in opposite directions at the same speed. The motor 41 and bearing supports 35 and 40 are rigidly mounted on a suitable base 45, which may be a board or partition in the cabinet of the machine.

A bracket indicated as a whole by 46 is fixed on the motorboard 33 back of the turntables. This bracket, which may be a single casting of aluminum, brass and the like, comprises a base 47 and a pair of side arms 48 and 49. Screws 50, 25 or other suitable fastening members, secure the base 47 rigidly to the motor board 33. The bracket arms 48 and 49 carry a pair of rods 51 and 52 which extend at their ends into openings in arms 48 and 49 and are secured by set-screws 53 and 54, respectively, or otherwise. The purpose of rod 51 is to support an electric reproducer indicated as a whole by R. This reproducer may be of any practical construction adapted to play on lateral-cut or vertical-cut records, as the case 35 may be. Since my invention is not limited to any special type of reproducer, and since, moreover, there are many makes of electric phonograph reproducers on the market for playing both kinds of records, I need not show or describe the 40 details of any particular construction of reproducer. It will therefore be understood that the reproducer R represents any practical form of device, electromagnetic, electrostatic or mechanical, for playing a phonograph record by means 45 of a stylus 55. For lateral-cut records, the stylus 55 is a pointed needle adapted to be clamped in a socket by a screw 56, according to the prevailing practice in devices of this kind. For vertical-cut records, like those of the Edison type, the 50 playing stylus is usually in the form of a diamond or sapphire point permanently attached to the reproducer casing.

The reproducer R is carried by an arm 57 which extends from a bearing sleeve 58 mounted 55 on rod 51 for rotary and axial movement by means of ball bearings 59, as best shown in the enlarged view of Fig. 10. The supporting rod 51 is so arranged that the playing point of stylus 55 traverses the spiral grooves of records 10 and 12 60 along the diametric line 21, to which reference was previously made in connection with Fig. 1. The rod 52 acts as a support for arm 57 when the reproducer is thrown back into idle or rest position, as indicated by the dotted outline 57' in 65 Fig. 4. The ball bearings 59 permit the reproducer R to travel axially along the rod 51 with a minimum amount of friction, and at the same time the reproducer is free to move up and down to accommodate itself to any inequalities in the 70 horizontal plane of the playing surfaces. It should be noted that the only propelling power for the reproducer is the spiral sound track, which moves the reproducer along the rod 51. Attention is called to the fact that the stylus 75

point 55 lies in a plane passing substantially through the center of sleeve 58, as shown in Fig. 6, whereby the pressure exerted by the stylus is distributed evenly through the sleeve for smooth 5 easy movement thereof along the rod 51. This plane is substantially at right angles to the axis of rod 51, irrespective of the fact that the rod holds the reproducer at an angle to the vertical when the reproducer is viewed from the side.

10 When I use only one pair of records 10 and 12, I provide means for automatically opening the circuit of motor 41 when the reproducer R reaches the end of its travel. Referring to Figs. 5 and 5a, the bracket arm 48 carries a suitable 15 switch indicated as a whole by S. In the present instance, this switch comprises an insulated spring contact 60 and a switch lever or arm 61 pivoted at 62 on a bracket 63. The spring contact 60 is mounted at one end on an extension 20 of bracket 63 by means of an insulating block 64. The pivoted arm 61 may be grounded to the bracket 63 and supporting arm 49. Circuit leads 65 and 66 are connected to the switch members 60 and 61. It is assumed that the conductors 25 65 and 66 are properly connected to the motor windings, as will be understood without illustration or description. If, as suggested, the contact arm 61 is grounded, one terminal of motor 41 may also be grounded, so that the separate 30 wire 66 is not necessary. A contracting coil spring 67 is connected at 68 to the switch lever 61 and at 69 to an extension 70 on bracket 63. When the switch lever 61 is closed, as shown 35 in Fig. 5a, the tensioned spring 67 holds it against a fixed pin or stop 71. The pivoted lever 61 is adapted to be moved to open position by an arm or extension 72 projecting rearwardly from the bearing hub 58 of reproducer R.

It is clear from Figs. 5 and 5a that, when the 40 reproducer R reaches a predetermined position on record 12, the arm 72 engages the free end of lever 61 and slowly rocks it toward the left, or in a clockwise direction as viewed in Fig. 5. The spring 67 is so close to the pivot point 62 of lever 45 61 that it does not interfere with the axial movements of the reproducer on supporting rod 51 as the stylus point is guided by the spiral sound groove 16. It requires only a slight rocking movement of lever 61 to throw the tension line 50 of spring 67 to the right of pivot 62, whereupon the spring 67 quickly moves the lever 61 into open position, as indicated by the dotted outline 61' in Fig. 5a. A stop 73 limits the movement of switch lever 61 into open position by the action 55 of spring 67. This lever is so positioned that the switch S is not opened until after the reproducer R has finished playing the record 12. It is perhaps best to arrange these cooperating parts in such a way that the switch S is opened 60 when the stylus of the reproducer enters the terminal groove 19 of record 12. It is a known fact that all phonograph records do not terminate at exactly the same point in the spiral track, and we may assume that the point 20 on record 65 12 (see Figs. 1 and 5) represents the farthest point to which the sound is recorded. Therefore, by automatically opening the motor switch S when the stylus of reproducer R enters the circular groove 19, premature stopping of the record 70 is prevented. An adjustable stop 74 may be mounted on the supporting bar 51 in such position that, when the bearing 58 engages this stop, the stylus 55 on being lowered enters the starting 75 groove 17 of record 10. To simplify Fig. 5 I have

omitted the spiral grooves 15 and 16 from the records.

I may provide my new phonograph apparatus with more than one pair of records, for the basic idea of my invention lends itself to the use of a 5 plurality of pairs of records which are automatically set in operation one after the other. A construction like that is illustrated more or less diagrammatically in Fig. 7, where we have two pairs of records 10-12 and 10'-12'. Since the 10 second pair of records 10'-12' and their driving connections are the same as those of the first 15 part of records 10 and 12, the detailed description of Figs. 5 and 6 may be considered to apply fully to the left half of Fig. 7. For this reason I have 15 indicated similar parts in the two halves of Fig. 7 by like reference numerals, except that, for the sake of distinction, certain numerals in the left half carry a prime mark ('). The reproducers R and R' are supposed to be identical in structure and mounting, but that is not necessary in the actual machine. These reproducers control certain switch mechanisms, which I shall now proceed to describe.

Referring to Figs. 4 and 10, the side arm 48 25 carries a bracket 75 on which an electromagnet 76 is mounted. The bracket 75 also supports a spring arm 77 terminating in a catch 78 and carrying an armature 79. The arm 72 projecting rearwardly from the bearing 58 of reproducer 20 R has a bevelled end 80 which normally engages the catch 78, as indicated by dotted lines 72' in Fig. 4. This locking engagement between the arm 72 and catch 78 holds the reproducer R sufficiently elevated to keep the point of stylus 35 55 above the surface of record 10, as indicated by the dotted outline 81 in Fig. 4. The stop 74 (see Fig. 10) is so adjusted that, when the bearing 58 is in its extreme right position on the supporting bar 51, the arm 72 is in alignment 40 with catch 78. The oppositely bevelled surfaces of these two members make it very easy to snap the arm into locking engagement with the catch, as may be seen in Fig. 4. When the electromagnet 76 is energized, the armature 79 is attracted 45 and the catch 78 is drawn out of engagement with the reproducer arm 72, whereby the reproducer R drops into playing position on record 10. As previously explained, the stop 74 is so adjusted that the point of stylus 55 enters the 50 circular starting groove 17 of the record when the reproducer is released by the electromagnet 76. The casing of reproducer R carries a movable switch arm 82, which is here shown as a substantially U-shaped spring blade grounded to 55 the metal framework of the casing. The normal set or tension of spring arm 82 holds it away from the insulated contact 83, which is also mounted on the reproducer casing by means of an insulating block 84. The preceding description is applicable to reproducer R' and electromagnet 76' which are associated with the second pair of records 10' and 12'.

The insulated switch contact 83 of reproducer R is connected in circuit by a conductor 85, which 65 leads to one side of the electromagnet 76', as diagrammatically indicated in Fig. 7. The spiral sound groove 16 of record 12 terminates in a depression 86, as best shown in Fig. 8. As long as the needle 55 rides in the spiral groove 16, the lower end 87 of the U-shaped arm 82 remains 70 out of contact with the surface of the record, so that the circuit of electromagnet 76' is open. When the end of spiral track 16 is reached and the needle 55 rides into the depression 86, the 75

rounded lower end 87 of the spring arm 82 engages the surface of the record, which is still rotating at the usual speed, as indicated by the arrow 88 in Fig. 8. When this occurs, the spring arm 82 is instantly moved against the contact 83 to close the circuit of electromagnet 76', which releases the reproducer R' into playing position, as previously explained in detail for reproducer R. In Fig. 7, the source of current for the electromagnets 76 and 76' is a battery 89, which is connected to one side of electromagnet 76 through conductors 92 and 124, and to one side of electromagnet 76' through conductors 90 and 91. The conductors 92, 93 and 124 may represent ground-
ed connections.

At the present time I prefer to hold the circuit of motor 41' open until just before the reproducer R of the first pair of records reaches the end of its travel. The circuit of motor 41' for the second pair of records is automatically closed through a suitable switch actuated by the arm 12 of reproducer R. The details of this switch are shown in Fig. 11, which I shall now describe. The side arm 49 of the supporting bracket 46 has a pair of extensions 94 and 95 carrying sleeves 96 and 97, which may be slidably mounted. Each sleeve has a slot 98 cooperating with a set-screw 99 to hold the sleeve in adjusted position on its supporting member. The sleeve 97 carries an insulated contact 100 to which a conductor 101 is connected. The sleeve 96 has a pin 102 on which two arms or levers 103 and 104 are pivoted for independent movement. The free end of arm 103 carries an insulated contact 104' to which a conductor 105 is connected. A contracting coil spring 106 is attached at 107 to the switch arm 103 and at 108 to the actuating lever 104. The sleeve 96 terminates in an extension 109, which carries a pair of stops 110 and 112. The spring 106 normally holds the arms 103 and 104 against the stops 110 and 112, respectively, whereby the switch contact 104' is in open position.

As the reproducer R approaches the end of its travel on record 12, the arm 12 encounters the free end of lever 104 and gradually moves it toward the left (see Fig. 11) until the tension line of spring 106 crosses the axis of pivot pin 102, whereupon the tensioned spring snaps the pivoted switch arm 103 into closed position, as indicated by the dotted line 103'. At the same time, the actuating lever 104 is thrown by the spring 106 into the dotted position 113' against the fixed stop 113 on sleeve 96. The engagement of switch contacts 100 and 104' closes the circuit of motor 41' through conductors 114, 115, 116 and 117. The plug 118 is supposed to be inserted in a socket of the house-lighting circuit. The closing of the motor switch 100-104' occurs before the stylus of reproducer R reaches the end of the spiral groove 16 on record 12, so that the second pair of records 10'-12' is running at full speed when the associated reproducer R' is dropped into playing position upon the energization of electromagnet 76'. It will thus be clear that the automatic circuit connections controlled by the movements of reproducer R first start the turntables of the next pair of records 10'-12' and then move the reproducer R' into playing position as soon as the reproducer R reaches the end of the sound groove in record 12. In this way, the second pair of records is automatically set in operation at the conclusion of the first pair of records, so that the reproduction is practically continuous from the time the reproducer R starts playing the first pair of records until the repro-

ducer R' is at the end of the second pair of records. The drop of the reproducers into playing position is very slight (see Fig. 4), being only a small fraction of an inch, so that no damage is done to the record. 5

If it is desired to use more than two pairs of records, it is only necessary to have the reproducer R' control a third pair of records and their associated reproducer in the same manner that the first reproducer controls the second reproducer, as above described. It is thus possible, in accordance with my invention, to construct an electric phonograph for automatically playing in succession any number of records without interruption, the reproducers being moved into 10 playing position one after the other at the right moment. 15

The circuit of motor 41 in Fig. 7 is closed through a switch indicated as a whole by 119, which is mounted on the side arm 49' of the 20 supporting bracket 46' associated with the second pair of records 10'-12'. The switch 119 may be considered a duplicate of the switch shown in Fig. 11. The motor circuit can be traced from conductor 116 through the closed switch 119, conductor 120, through the windings of motor 41, and the return conductor 117. After the reproducer R has reached its final position and the second pair of records 10'-12' has been set in 25 operation, an attendant opens the switch 119 by 30 merely throwing the pivoted lever 121 to the right. To avoid unnecessary repetition, I need only explain that the lever 121 of switch 119 corresponds to the pivoted lever 104 in Fig. 11. When the switch 119 is opened, the turntables of records 35 10 and 12 stop, and the attendant may now put on a new pair of records and move the reproducer R to starting position against the stop 74. The reproducer R is placed in holding engagement with the associated catch 78, so as to be held 40 out of contact with the new record 10, as previously explained in connection with Fig. 4.

When the second reproducer R' approaches the end of its travel, the arm 12 on mounting 58 moves the switch lever 121 into closing position, 45 precisely as described in connection with Fig. 11. The closing of switch 119 starts the motor 41. When the stylus 55 of reproducer R' enters the terminal depression 86 in record 12', as explained in the description of Fig. 8, the switch arm 82 50 is actuated to close the circuit of electromagnet 76 through conductors 90, 122 and 123, through coil of electromagnet 76, and to the battery 89 through conductors 124 and 92. The energizing of electromagnet 76 permits the reproducer R to 55 drop into playing position on the rotating record 10, so that the reproduction continues with substantially no interruption from the point where the reproducer R' left off. After the new pair of records 10 and 12 have thus been set in operation, the attendant moves the switch lever 104 from the actuated position 113' (see Fig. 11) to its normal position to open the switch arm 103 and thereby stop the turntables of records 10'-12'. This gives the attendant an opportunity to change the second pair of records for a new pair on which the recording is supposed to be a continuation of the records played by the reproducer R. It is thus seen that one attendant can change the records in pairs, so as to make 70 possible a continuous reproduction from any number of pairs of records. This apparatus is particularly useful for talking movies in which a long film of several reels is accompanied by synchronized music and speech. 75

When more than one pair of records are used, the records of the different pairs and their respective turntables are provided with cooperating holes and pins to prevent the placing of a record 5 on the wrong turntable. For example, the records 10 and 12 of the first pair have positioning holes 29 and 30, which make it impossible to place these records on any turntable except the ones for which they are intended. In like manner, the 10 records 10' and 12' of the second pair have holes 29' and 30' respectively, which fit only over pins on the second pair of turntables. As a further means of facilitating the correct positioning of the records, they may be identified by different 15 colored labels. To give an illustration, the records intended for the first pair of turntables may have a red label in the center, while the records for the second pair of turntables may have a green label, and so on for other pairs of records. No 20 special care is required to place the reproducers R and R' in correct supporting position, because the adjustable stops 74 limit the movement of the reproducers on their supporting rods 51. If the diameter of the starting grooves 17 on the first 25 record of each pair should vary in different sets of records, it is only necessary to adjust the stop 74 into correct position. Likewise, if the terminal grooves 19 of the second records of each pair should vary in diameter, the sleeve 96 may be 30 adjusted to cause the arm 12 to close the motor circuit of the next pair of turntables at the proper moment. The position of sleeve 97 is adjustable to take care of any adjustments of sleeve 96.

35 Although I have shown and described certain specific constructions, I want it understood that my invention is not limited to the details set forth. I realize that changes and modifications will probably occur to those skilled in the art, because 40 the basic features of my invention are susceptible of various embodiments without departing from the scope of the invention as defined in the following claims.

I claim as my invention:

45 1. A phonograph having means for supporting two disk records for simultaneous rotation in opposite directions, one of said records being played from the center toward the edge and the other record being played from the edge toward 50 the center, a pickup mounted in operative relation to said records, and means whereby said pickup plays the records successively and substantially without interruption, said last-mentioned means including means enabling the pickup to travel automatically from one record to the next.

55 2. In a phonograph, the combination of two disk records having a substantially continuous stylus groove running in two oppositely curved spirals from the center of one record to the center 60 of the other, said records being simultaneously rotatable in opposite directions.

3. A phonograph having two turntables connected to rotate simultaneously in opposite directions at the same speed, said turntables being 65 adapted to support records in substantially the same horizontal plane, a single pickup mounted in operative relation to said records, and means whereby said pickup automatically travels from one record to the next, said last-mentioned means 70 including means for automatically guiding the pickup stylus from the sound groove of one record to that of the next.

75 4. In an electric phonograph, the combination of a disk record in which the spiral sound track terminates in a depression, the surface of said

record being wholly of insulating material, an electric reproducer for said record, and a pair of normally open switch contacts carried by said reproducer, one of said contacts being so arranged as to be engaged by the insulated surface 5 of the record and moved against the other contact when the stylus point of the pickup enters said depression.

5. In a phonograph, the combination of a pair of disk records having each a spiral sound track 10 running to the very edge of the disk, and means for so mounting said disks that their spiral tracks unite at the edge.

6. In a phonograph, the combination of a pair of disk records mounted to rotate simultaneously 15 in opposite directions and in contact at the edge, and interlocking means at the edges of said records to hold them in alignment.

7. A phonograph having two turntables connected to rotate simultaneously in opposite directions at the same speed, a pair of disk records mounted on said turntables in predetermined relation to each other, one of said records having a spiral groove arranged to be played from the center toward the edge and the other record having a spiral groove arranged to be played from the edge toward the center, and electric reproducing means controlled by said grooves.

8. In a phonograph, the combination of a pair of oppositely rotating disk records, one of which 30 is played from the center toward the edge and the other is played from the edge toward the center, a separate turntable for supporting each record, means for rotating said records simultaneously in opposite directions, a reproducer operatively associated with said records, and means whereby the stylus of said reproducer automatically travels from the groove of one record to the groove of the other.

9. In a phonograph, the combination of a pair 40 of turntables connected to rotate simultaneously in opposite directions, a pair of disk records adapted to be mounted on said turntables, said records having each a spiral sound track running to the very edge of the disk, and cooperating means on 45 said turntables and records for so mounting the latter that their spiral tracks unite at the edge.

10. In a phonograph, the combination of two disk records mounted in substantially the same plane to rotate simultaneously in opposite directions, said records being in contact at the edge and having spiral grooves united at the point of contact, whereby said united grooves form a substantially continuous stylus track from the center 50 of one record to the center of the other, and a 55 single reproducing means for playing both records.

11. In a phonograph, the combination of two disk records mounted in substantially the same plane to rotate simultaneously in opposite directions, said records being in contact at the edge and having spiral grooves united at the point of contact, whereby said united grooves form a substantially continuous stylus track from the center 60 of one record to the center of the other, and a 65 reproducer so mounted that its stylus point travels in said track along a diametric line connecting the centers of said records.

12. A phonograph having means for supporting two disk records for simultaneous rotation in 70 opposite directions, one of said records being played from the center toward the edge and the other record being played from the edge toward the center, a single reproducer for playing both records, means for mounting said reproducer so 75

- that it travels along a diametric line connecting the centers of said records, and means whereby the stylus of said reproducer automatically travels from one record to the other.
- 5 13. A phonograph having two turntables connected to rotate simultaneously in opposite directions at the same speed, a pair of disk records mounted on said turntables in predetermined relation to each other, one of said records being 10 played from the center toward the edge and the other record being played from the edge toward the center, in combination with a single reproducer for playing both records, said predetermined relation of the records being such that the 15 stylus point automatically travels from the groove of one record to the groove of the other.
14. An electric phonograph comprising at least two pairs of turntables adapted to support disk records, the records of each pair being in contact 20 at the edge and having a substantially continuous sound groove running from the center of one record to the center of the other, connections for driving each pair of turntables in opposite directions, an electric reproducer for playing 25 the first pair of records, a second electric reproducer for playing the second pair of records, means for holding the second pair of records and the associated reproducer inoperative while the first reproducer is playing, and means operable 30 when the first reproducer reaches the end of its sound groove for automatically placing the second pair of records and the associated reproducer in operative condition.
15. An electric phonograph comprising at least 35 two pairs of turntables adapted to support disk records, the records of each pair being in contact at the edge and having a substantially continuous sound groove running from the center of one record to the center of the other, connections for 40 driving each pair of turntables in opposite directions, an electric reproducer for playing the first pair of records, a second electric reproducer for playing the second pair of records, means for holding the second reproducer in an inoperative 45 position while the first reproducer is playing, and means operable when the first reproducer reaches the end of its sound groove for automatically causing the second reproducer to move 50 into playing position.
16. An electric phonograph comprising at least 55 two pairs of turntables adapted to support disk records, the records of each pair being in contact at the edge and having a substantially continuous sound groove running from the center of one record to the center of the other, an electric motor for driving each pair of turntables in opposite directions, an electric reproducer for playing the first pair of records, a second electric reproducer for playing the second pair of records, means 60 for holding the second reproducer in an inoperative position while the first reproducer is playing, means operable when the first reproducer reaches the end of its sound groove for automatically causing the second reproducer to move 65 into playing position, a normally open switch for the electric motor of the second pair of turntables, and means whereby the first reproducer closes said switch to start the motor before the second reproducer is moved into playing 70 position.
17. In a phonograph, the combination of a record provided with an operative portion at the end of its sound groove, and an electric reproducer carrying a fixed contact and a movable 75
- switch arm normally out of engagement with said contact, said switch arm being normally out of engagement with the record and movable into closing position by said operative portion of the record. 5
18. In a phonograph, the combination of a record provided with an operative portion at the end of its sound groove, and an electric reproducer carrying a fixed contact and a substantially U-shaped spring arm normally out of engagement 10 with said contact, said switch arm being normally out of engagement with the record and movable into closing position by said operative portion of the record.
19. A phonograph having a stationary support 15 which carries a plurality of turntables for holding disk records in playing position, pickup mechanism for playing said records, an electric motor for simultaneously rotating said turntables and records, and means controlled by the position of 20 said pickup mechanism for automatically opening the motor circuit when the last record is played through.
20. In a phonograph, the combination of a pair 25 of disk records supported for operative movement, the playing surfaces of said records being in substantially the same plane, and an electric reproducer mounted to travel in a rectilinear path from one record to the other, said reproducer being so mounted that the path of the stylus is substantially 30 in a line connecting the centers of said disk records.
21. A phonograph having a rod supported over 35 the topboard, a bracket slidably and pivotally mounted on said rod, an electric reproducer carried by the front end of said bracket, a rear extension on said bracket, and a releasable latch supported independently of said reproducer and adapted to engage said extension for holding said reproducer out of playing contact with a record 40 only when the reproducer is in a predetermined starting position.
22. A phonograph cabinet having a top-board, a plurality of turntables supported on shafts which extend through the topboard, an electric 45 motor for rotating said shafts, electric pickup mechanism movably mounted in operative relation to records on said turntables, means whereby said mechanism plays said records in automatic sequence and substantially without interruption, and means for automatically opening the motor circuit when the last record is played 50 through.
23. A phonograph having means for operatively supporting a record, a reproducer for playing 55 said record, an electric switch mounted entirely on said reproducer and comprising a relatively fixed contact and a movable spring arm normally in open position and out of engagement with the record surface, which is formed with a depression 60 arranged to receive the stylus at the end of the sound groove, the entry of the stylus into said depression causing the reproducer to drop toward the record and carry said spring arm into engagement with the record, whereby the spring arm is 65 automatically moved against said contact to close the switch, and an operative circuit controlled by said switch. 60
24. Acoustic apparatus comprising a turntable for supporting a disk record, an arm pivoted intermediate its ends for vertical movement and supported for horizontal sliding movement, a stylus-holding head mounted on one end of said arm in operative relation to a record on said turntable, latching means arranged to engage the 70
- 75

other end of said arm for holding said head raised to keep the stylus out of contact with a record on the turntable, and means for automatically causing said latching means to release the arm at a predetermined moment, whereupon the stylus descends to operative position on the record, said latching means holding the stylus out of contact with a record only when the stylus is in a predetermined starting position.

25. In electric recording and reproducing apparatus, a stylus head carrying a pair of switch contacts, one of which is a substantially U-shaped spring arm adapted to be operated by engagement with a record, and an operative circuit controlled by said contacts.

ADOLPH A. THOMAS.
